UNITED STATES PATENT OFFICE.

AMASA LYON, OF NEW YORK, N. Y.

DESIGN FOR A PARASOL-LINING.

SPECIFICATION forming part of Design No. 15,160, dated July 22, 1884.

Application filed December 28, 1883. Term of patent 7 years.

To all whom it may concern:

Be it known that I, AMASA LYON, of the city, county, and State of New York, have invented and produced a new and original Design for Parasols; and I do hereby declare that the following is a full and exact description thereof, reference being had to the accompanying drawings, and to the letters of reference marked thereon, making a part of this specification.

Figure 1 is a view in perspective of my newly-designed parasol, and Fig. 2 is a sectional view illustrating its configuration more clearly.

Heretofore open parasols have generally been of a concavo-convex form, and occasionally this has been varied by the intersection of a plane surface with the concavity, substantially as indicated by the positive line xx in Fig. 2.

The leading feature of my design consists in a conoidal projection upon the inner under side of an open parasol, extending from about the middle of the cover, with an inwardly-curved outline, to an apex at the central stick of the parasol.

A is the extended cover of the open parasol or umbrella, whose outer surface is of the usual circular convex form, broken into transverse curves at its circumference, which lose them-

selves in the simple smooth dome shape of the center.

B is an inner projection presenting a conoidal surface having its apex C at the central stick, D, and which extends from said apex, with an outwardly-flaring outline, until it intersects the under side of the radial curve of the cover A in a circle about midway the same. The line of intersection of the base ee of this conoidal projection with the contour of the cover A is slightly indented to conform to the indentations or transverse curves of the cover. (See Fig. 1.) These indentations are, however, quickly merged and lost in the smooth surface which characterizes the apical portion of the conoidal projection.

I claim as my invention—

The design for an open parasol herein shown and described, consisting of a concavo-convex cover, A, and a conoidal projection, B, extending, with a re-entrant curve, from about midway between the center and circumference of the inner side of said cover to a central apex, C.

In testimony whereof I have signed my name to this specification in the presence of two subscribing witnesses.

AMASA LYON.
